CLAIM

The ornamental design for a nozzle for use with a blow molder, as shown and described.

DESCRIPTION

FIG. 1 is a perspective view of a top side of a nozzle for use with a blow molder according to my new design;

FIG. 2 is a front view thereof;

FIG. 3 is a rear view thereof;

FIG. 4 is a side view thereof;

FIG. 5 is a side view thereof, from a side opposite that of FIG. 4;

FIG. 6 is a top view thereof;

FIG. 7 is a bottom view thereof; and,

FIG. 8 is a bottom perspective view thereof, from a different angle than that of FIG. 1.

The broken lines shown in the drawings are for the purpose of illustrating a portion of the nozzle that forms no part of the claimed design.
